M. W. MAGANN

GAS ENGINE CONSTRUCTION

Filed Dec. 24, 1920

Fig. 1.

Inventor:
Merritt W. Magann.
By Elliott V. Thorne
Atty's.

UNITED STATES PATENT OFFICE.

MERRITT W. MAGANN, OF ST. LOUIS, MISSOURI.

GAS-ENGINE CONSTRUCTION.

Application filed December 24, 1920. Serial No. 432,924.

To all whom it may concern:

Be it known that I, MERRITT W. MAGANN, a citizen of the United States, residing in the city of St. Louis and State of Missouri, have invented new and useful Improvements 5 in Gas-Engine Constructions, of which the following is a specification.

This invention relates to the construction of gas-engines, and particularly concerns the 10 construction of their cylinders and pistons. It is a well-known fact that the wear on gas-engine cylinders occasioned by the reciprocation of the piston is very great. This is due partly to the high temperature within 15 the cylinder, and to the fact that the use of a sufficient quantity of lubricating oil tends to produce carbonization in the cylinders. Such wear causes a reduction in the efficiency and also necessitates the reboring of the 20 cylinders from time to time. The general object of the present invention is to overcome this difficulty and to provide simple means for guiding the piston within the cylinder without subjecting the cylinder to 25 unnecessary wear and at the same time to provide means for effecting the lubrication of the sliding parts which will operate in such a way as to prevent or tend to prevent the formation of carbon within the cylinder. 30

Further objects of the invention will appear hereinafter.

The invention consists in the novel features, and in the general combination of 35 parts to be particularly described hereinafter, all of which contribute to produce a simple and efficient gas-engine construction. A preferred embodiment of my invention will be particularly described in the following specification, while the broad scope of 40 my invention will be pointed out in the appended claims.

In the drawing,

Figure 1 is a vertical cross-section through 45 the cylinder of an engine to which my invention has been applied; and

Figure 2 is a vertical section taken about on the line 2—2 of Figure 1, but showing the fork end of the connecting-rod in elevation, and broken away.

My invention may be applied to a cylinder of an engine of almost any construction if the engine is of the common type of gas-engine in which the end of the cylinder toward the shaft is open. It may be applied 55 to engines operating on the two-cycle or

four-cycle principle. In order to apply the invention to such an engine it is simply necessary to remove the piston and provide my special piston and guiding means, such 60 as the bushing which I provide. The invention may be readily embodied in the design of a new engine.

For the purpose of illustration, in the accompanying specification and drawing, I 65 have represented the invention as applied to an engine that is supposed to have been already built.

In the drawing, 1 represents one of the vertical cylinders of a multi-cylinder gas-engine, the lower ends of the cylinders being supported on a crank-case 2. Within the bore of the cylinder 1, I provide a piston 3, and this piston comprises a transverse disc or head 4 at its outer or upper end and a 70 cylindrical shell 5 which may be cast integrally with the head, and extends inwardly therefrom. This piston 3 is ringless, that is to say, it presents an uninterrupted cylindrical face extending from the head 4 to 75 its lower end 6.

The usual means for attaching a connecting-rod to a piston is a transverse wrist-pin which passes through the side walls of the piston, and the force exerted by the piston 85 is imparted through the side walls to the pin, and thence to the connecting-rod. According to my invention I provide the piston with an unobstructed bore 7 which extends from the inner end 6 clear up to the 90 head 4, and the attachment of the connecting rod 8 to the piston is effected through the medium of a post 9 which is preferably of conical form, the upper or outer end of the cone being the large end and formed integrally with the head of the piston. The lower or inner end of the post carries an integral boss or sleeve 10 which is drilled to receive a wrist pin 11 which connects the 95 forks 12 of the connecting rod (see Fig. 2). The wall of the post or cone 9 may be provided with an opening, such as the opening 13 which lessens the weight of the piston and which also enables the core to be supported within the mold when the piston is 105 cast. The piston shell 5 is provided at one side with an opening 14 through which the pin 11 may be introduced.

In order to guide the piston independently of the cylinder 1, I provide a guide 110 in the form of a guide-bushing 15 the inner end of which is fixed to some part of the

engine casing. I prefer to provide the bushing with an annular shoulder 16 which is of the proper diameter to fit snugly into the lower end of the bore 1^a of the cylinder. 1. This operates to insure exact centering or alignment of the bushing within the cylinder. The lower or inner end of the bushing is provided with a flange 17 which may be secured by suitable bolts 18 to the end 10 of the cylinder that projects into the engine casing. The bushing 15 is of a diameter to fit neatly within the bore 7 of the piston 3 and as the piston descends a telescoping action takes place between the 15 piston and bushing. Of course there is formed between the bore 1^a and the bushing 15, an annular space 19 which receives the lower end of the piston as it descends. The packing of the piston is effected between the bushing and the bore 7 of the 20 piston 3 instead of on the outer face of the piston. For this purpose, I provide packing rings 20 mounted in suitable annular grooves. For lubrication of the contact 25 surfaces of the bushing and piston I depend upon the splashing up of the lubricating oil from a bath, the level of which is indicated by the line 21. This bath is carried in the bottom of the crank-case, in 30 the usual way and as it is struck by the cranks 22 of the engine, the lubricant is splashed up into the interior of the piston. Quantities of it come in contact with the bore 7 and find their way down toward the 35 packing rings 21. I prefer however, to provide means to prevent the largest quantity of this oil from passing down into the annular space 19. This, of course, operates to prevent movement of the oil into the interior of the cylinder where the explosion 40 takes place. For this purpose I prefer to provide the upper portion of the bushing with a plurality of drip-openings 23. These preferably incline downwardly toward the 45 bore of the bushing, and if desired, may be located just above the rings 20.

In the operation of the engine, of course, any escape of gas past the piston within the cylinder would eventually be prevented 50 at the packing rings 20.

It is understood that the embodiment of the invention described herein is only one of the many embodiments my invention may take, and I do not wish to be limited 55 in the practice of my invention nor in my claims, to the particular embodiment set forth.

In practice I prefer to construct the piston 4 of Iyanite and the bushing of 60 brass; when the bushing has become greatly worn, then it can be replaced by a bushing of larger diameter. This substitution can

be readily effected without putting the engine out of commission more than an hour or so.

It is obvious that the guide 15 may be cast integral with the wall of the cylinder 1, provided the cylinder head is cast separate to permit the machining of the guide and the bore of the cylinder. This machining could be accomplished by means of a miller of sleeve form. It is also obvious that any desired pressure-lubricating-system may be employed with my engine construction.

What I claim is:

1. In a gas-engine, the combination of a crank-case adapted to carry a bath of lubricating oil, a cylinder mounted in the crank-case and having a cylindrical shell with a bore open at its inner end, a fixed guide-bushing projecting into the bore of the piston from the inner end of the cylinder, whereby an annular space is formed between the cylinder wall and the bushing, said bushing having drip-openings through the wall thereof operating to prevent quantities of the lubricating oil from passing into the annular space between the bushing and the cylinder wall, and packing rings carried by the bushing.

2. In a gas-engine, the combination of a cylinder, a piston mounted to reciprocate therein, having a head and a cylindrical shell extending inwardly from the head with its bore open at its inner end, a fixed guide-bushing projecting into the bore of the piston from the inner end of the cylinder, operating to guide the piston within the cylinder, a post of substantially conical form, having its base integrally connected with the head, said post projecting inwardly, a connecting rod connected at one end to the crank of the engine and a wrist-pin fastened to the upper end of the connecting rod and through the inner end of the post.

3. In a gas-engine, the combination of a cylinder, a piston mounted to reciprocate therein, having a head and a cylindrical shell extending inwardly from the head with its bore open at its inner end, a fixed guide-bushing projecting into the bore of the piston from the inner end of the cylinder, operating to guide the piston within the cylinder, a hollow substantially conical post having its base integrally connected with the head and extending inwardly, a connecting rod attached to the crank shaft at one end, and a wrist-pin passing through the inner end of the post and through the outer end of the connecting rod.

In testimony whereof, I have hereunto set my hand.

MERRITT W. MAGANN.
